BIRD FEEDER

Ralph H. Bower, Goshen, Ind., assignor to The Bower Manufacturing Co., Inc., Goshen, Ind.

Filed Oct. 8, 1971, Ser. No. 187,941

Term of patent 14 years

Int. Cl. D30—03
U.S. Cl. D30—15

FIG. 1 is a front elevational view of a birder feeder, showing my new design, the rear being substantially a mirror image thereof;

FIG. 2 is a right side elevational view, the opposite side being substantially a mirror image thereof;

FIG. 3 is a bottom plan view;

FIG. 4 is a cross-sectional view partly in top plan taken along line 4—4 in FIG. 1 and looking in the direction of the arrows; and

FIG. 5 is a partial cross-sectional view partly in front elevation taken substantially along the line 5—5 in FIG. 4 and looking in the direction of the arrows.

The perch rod has been partially broken away and omitted in FIGS. 1, 3, 4 and 5 for convenience in illustration.

I claim:

The ornamental design for a bird feeder, substantially as shown and described.
